UNITED STATES PATENT OFFICE.

PAUL W. RUNYAN, OF SPRINGFIELD, OHIO, ASSIGNOR TO THE NATIONAL BROODER COMPANY, OF SPRINGFIELD, OHIO, A CORPORATION OF OHIO.

DESIGN FOR A BROODER STOVE.

Application filed April 21, 1924. Serial No. 9,335. Term of patent 14 years.

To all whom it may concern:

Be it known that I, PAUL W. RUNYAN, a citizen of the United States, residing at Springfield, in the county of Clark and State of Ohio, have invented a new, original, and ornamental Design for Brooder Stoves, of which the following is a specification, reference being had to the drawing forming part thereof.

The figure is a perspective view of a brooder stove embodying the invention.

I claim:

The ornamental design for a brooder stove as shown.

PAUL W. RUNYAN.
